UNITED STATES PATENT OFFICE.

PATRICK J. HUNT, OF NEW BEDFORD, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed March 29, 1922. Serial No. 547,620.

To all whom it may concern:

Be it known that I, PATRICK J. HUNT, a citizen of the United States, residing at New Bedford, in the county of Bristol and State 5 of Massachusetts, have invented an Improvement in Feeler Mechanisms for Looms, of which the following description, in connection with the accompanying drawings, is a specification, like characters on the drawings representing like parts.

This invention relates to feeler mechanisms for looms whereby the operative condition of the loom is changed from time to time.

15 In feeler mechanisms wherein the feeler enters the shuttle and engages the filling on detecting beats of the lay, the recurring impacts of the feeler against the filling are liable to injure the latter, especially where 20 the yarn is "tender" as in cop filling. The injurious effect of the recurring impacts of the feeler are also observable in shuttles containing soft or very fine filling, especially where the feeler itself is provided with teeth 25 for engaging the filling. Injury is liable to occur to the filling carrier in the shuttle in that type of feeler mechanism wherein the feeler is moved longitudinally of the filling carrier when filling is to be changed. Moreover, in cop filling carriers the character of 30 the carrier itself does not present a surface along which the feeler may be moved when the filling is substantially exhausted.

One of the objects of the present invention 35 is to provide a feeler mechanism wherein the feeler and shuttle shall be constructed and arranged so that the recurring impacts of the feeler against the filling may be avoided, and when the feeler calls the change 40 of filling by sliding movement longitudinally of the shuttle, the filling carrier itself will be protected from injury.

In accordance with the present invention, 45 the feeler is mounted to enter the shuttle on detecting beats and the shuttle has an opening for the entrance of the feeler, which opening is covered by a flexible curtain to protect the filling in the shuttle and present a surface along which the feeler may slide 50 when it partakes of its side-slipping movement.

In the drawings:

Figure 1 is a perspective view of sufficient portions of a loom with the present inven-

tion associated therewith to make clear the 55 relation and operation of the parts;

Fig. 2 is a cross section through the shuttle at the curtain-protected opening, showing more particularly the bodily movement of the flexible curtain by the feeler when a 60 working supply of filling is present in the shuttle;

Fig. 3 is a detail with parts broken away, showing the feeler and its action when used in connection with a cop filling carrier. 65

The replenishing mechanism by which a fresh supply of filling is placed in the shuttle from time to time, is not herein illustrated, nor is the entire train of mechanism between the feeler and filling replenishment mechanism illustrated, because the details of each of these mechanisms are unimportant so far as the present invention is concerned, and may be of well known character. 70

The feeler of the present invention is of 75 the side-slipping type, and in the illustrated form of the invention it is shown as entering the shuttle in a direction inclined to the longitudinal axis of the shuttle on a detecting beat. Certain advantages incident 80 to the present invention are more fully observable in the inclined type of feeler, but the present invention is not restricted to this type, because feelers of other character or type may be employed in connection with 85 the other features of the invention.

The loom frame has extending therefrom the bracket 1 of usual character, provided with a slot 2 through which passes the bolt 3 for adjustably connecting the feeler stand 90 4 with the feeler mechanism in operative position.

The supporting portion 5 of the bracket 4 has secured thereto the feeler stand 6 provided with the usual opening 7 and bolt 8 95 for securing the parts in adjusted position. The feeler stand 6 serves as a support for the feeler and, as shown, is provided with the swivel bearing 9 pivotally mounted at 10 between the bracket 11 and the feeler stand, 100 through which the front end portion of the feeler 12 extends.

The rear portion of the feeler stand is provided with a rear bearing 13 provided with a guideway for the slide 14 having a 105 slotted portion 15 for the reciprocation frontwardly and rearwardly of the feeler 12. The feeler slide 14 is connected by a transmitter

16 to the usual train of mechanism for effecting replenishment of filling. The parts so far described may be of the same general construction as shown and described in the 5 patent to Edward S. Stimpson, No. 1,309,226, dated July 8, 1919, the construction being such that upon side-slipping movement of the feeler 12 in a direction longitudinally of the shuttle, filling replenishment will be 10 called.

The lay 17 is provided with the usual shuttle-box 18 at the detecting side thereof, and the front wall 19 of the shuttle-box has an opening 20 for the passage of the feeler. 15 The shuttle 21 is provided with the holding jaws 22 which engage the usual rings 23 on the head portion of the filling carrier.

In the illustrated form of the invention, the filling carrier 24 is shown as of the type 20 for holding cop filling, which is usually of tender yarn, and while the advantages of the invention are observable in this connection, the invention of course is not restricted to the use of cop filling carriers, but the 25 usual bobbin may be employed in some instances and secure the advantages of the present invention.

The shuttle 21 has the opening 25 for the entrance of the feeler in discharging its feel- 30 ing function as usual, and interposed between the end of the feeler and the filling carrier in the shuttle is a protector curtain which is engaged by the end of the feeler on a detecting beat and bodily moved inwardly, 35 the effect being that the fine, soft, or tender filling in the shuttle will not be injured by the recurring impacts of the feeler against it. The flexible curtain also extends longitudinally over the opening in the shuttle to an extent sufficient to provide a sliding 40 surface along which the end of the feeler may slip while in engagement therewith when the feeler partakes of its side-slipping movement. Thus in case a bobbin is employed in 45 the shuttle, its surface is protected from engagement by the end of the feeler, and in case of a cop filling carrier being in the shuttle, a surface is presented along and over which the end of the feeler may slide 50 when it is displaced laterally.

The flexible curtain 26 may be formed of material of yielding character, such for instance, as leather, rubber, or composition, and is secured to the shuttle to permit its 55 bodily movement inwardly by the end of the feeler on a detecting beat.

The flexible curtain 26 has secured to it the flexible strips whereby it is held in position over the opening in the shuttle and yet 60 permitted its bodily movement inwardly by the feeler. As shown in Fig. 1, the flexible curtain 26 has secured to its upper edge at 27, a flexible strip 28 which extends longitudinally of the shuttle and is secured at 65 points remote from the curtain 26 as at 29,

and 30, to the inside of the shuttle. As shown, the connection between the curtain 26 and the flexible strip 28 is effected by sewing the two parts together, although other means of connecting the parts will 70 suggest themselves. The lower edge portion of the flexible curtain 26 is secured in like manner along the portion 31 to a similar flexible strip 32 which extends longitudinally of the shuttle and is secured to the 75 inside portion of the shuttle at 33 and 34 at points remote from the curtain or opening in the shuttle. The flexible strips 28 and 32 may be formed of elastic material if desired, such for instance as rubber web or the like, the purpose being to permit the flexible curtain 26 to be bodily displaced inwardly as indicated in Fig. 2 when engaged by the feeler on a detecting beat.

The flexible curtain 26 extends longitudinally of the shuttle to present a bearing surface to the end of the feeler as indicated in Fig. 3, and along which the end of the feeler may slip or slide when it is displaced laterally to effect replenishment of filling. 80 Thus the flexible curtain 26 not only protects the filling in the shuttle from the injurious direct contact of the feeler on detecting beats, but when the feeler moves longitudinally of the shuttle or is displaced laterally, the end of the feeler will slide along the curtain out of engagement with the filling carrier in the shuttle. 95

The flexible curtain 26 is preferably, 100 though not necessarily, formed of leather, because leather presents not only the flexible character desired for the curtain, but also a frictional surface for engagement by the feeler to prevent movement of the feeler longitudinally of the shuttle by frontward 105 pressure in case the feeler is of the inclined type. Preferably, also, the flesh side of the leather curtain 26 will be presented for contact by the feeler as it offers the desired frictional character of surface which acts 110 on the end of the feeler to prevent displacement of the feeler longitudinally of the shuttle when a working supply of filling is present in the shuttle.

As shown in Figs. 1 and 3, the engaging 115 end portion 35 of the feeler is devoid of teeth, and has a rounded or smooth surface which, by frictional engagement with the surface of the flexible curtain, prevents displacement of the feeler in a direction longitudinally of the shuttle by the frontward pressure, where the feeler is of the inclined type. Should the feeler be of the caliper- 120 ing or measuring type and be mounted for movement longitudinally of the filling, its rear 125 or engaging end portion may advantageously be made smooth or without teeth.

Associated with the feeler 12 is an auxiliary feeler finger which, when the filling in the shuttle is substantially exhausted on a 130

detecting beat, and the feeler therefore enters the shuttle to an abnormal extent, engages a surface on the lay, the wall of the shuttle in the present illustration, and is moved longitudinally of the shuttle to thereby produce lateral or sliding movement of the feeler. The auxiliary feeler finger has its engaging end 36 offset from the feeler, and is preferably made rounded as indicated in Figs. 1 and 3. The stem portion 37 of the auxiliary feeler finger is mounted in a lug 38 carried by the feeler, and is adjusted relatively thereto by means of the adjusting nuts 39, one at each side of the lug 38.

When a working supply of filling is present in the shuttle on a detecting beat, the feeler engages the flexible curtain 26 and bodily deflects the curtain inwardly against the filling and then is moved frontwardly against the action of its normally-acting spring 40 which permits such frontward movement of the feeler and serves to return the feeler to its rearward feeling position as the lay goes back. Thus on the recurring beats of the lay, the filling in the shuttle, even though it be of fine or soft character such, for instance, as cop filling or silk, is not injuriously affected because the flexible material of the curtain 26 cushions the blow without permitting direct contact of the feeler with the filling. When filling is substantially exhausted on a detecting beat, the flexible curtain 26 will again be deflected bodily inwardly, as the lay beats up, and substantially into the position indicated in Fig. 3, and then the end 36 of the auxiliary feeler finger will engage the shuttle or other surface carried by the lay and by frontward pressure thereagainst, cause the auxiliary finger and perforce the attached feeler, to be moved longitudinally of the shuttle, the smooth end portion 35 of the feeler at such times sliding along in contact with the surface of the flexible curtain. Thus the flexible curtain serves not only to protect the filling in the shuttle from injurious contact by the feeler on detecting beats, but affords protection to the surface of the filling carrier in the shuttle from sliding contact with the end of the feeler when the latter partakes of its side-slipping movement.

What is claimed is:—

1. In a feeler mechanism for looms, the combination of a feeler that is mounted for side-slipping movement and also for movement toward and from the front of the loom, a shuttle having a side opening through which the feeler passes on a detecting beat, and a protector curtain of flexible material interposed between the end of the feeler and the filling carrier in the shuttle and along which the feeler slides in a direction longitudinally of the shuttle when filling is substantially exhausted on a detecting beat thereby protecting the filling and
2. In a feeler mechanism for looms, the combination of a feeler that is mounted for side-slipping movement and also for movement toward and from the front of the loom, a shuttle having a side opening through which the feeler passes on a detecting beat, a protector curtain of flexible material interposed between the end of the feeler and the filling carrier in the shuttle and along which the feeler slides in a direction longitudinally of the shuttle when filling is substantially exhausted on a detecting beat thereby 70 protecting the filling and the filling carrier from injury by the feeler during both its feeling action and side-slipping movements, and an auxiliary feeler finger carried by the feeler to engage the shuttle and cause the 75 end of the feeler to slip along the flexible curtain in engagement therewith.
3. In a feeler mechanism for looms, the combination of a feeler that is mounted for side-slipping movement and also for movement toward and from the front of the loom, a shuttle having a side opening through which the feeler passes on a detecting beat, a protector curtain of flexible material interposed between the end of the feeler and the filling carrier in the shuttle and along which the feeler slides in a direction longitudinally of the shuttle when filling is substantially exhausted on a detecting beat thereby 80 protecting the filling and the filling carrier from injury by the feeler during both its feeling action and side-slipping movements, and an auxiliary feeler finger carried by the feeler to engage the shuttle and cause the 85 end of the feeler to slip along the flexible curtain in engagement therewith.
4. In a feeler mechanism for looms, the combination of a feeler that is mounted for side-slipping movement and also for movement in a direction toward and from the front of the loom, a shuttle having an opening for the entrance of the feeler on a detecting beat, a protector curtain of flexible material which is secured to the shuttle to cover 90 the entrance opening and extends longitudinally of the opening to form a bearing for the end of the feeler for its full side-slipping movement to protect the filling and filling carrier from injurious contact by the feeler, 95 and means for replenishing the filling when the feeler slides along the flexible curtain on a detecting beat.
5. In a feeler mechanism for looms, the combination of a feeler that has a smooth rear end and is mounted for side-slipping movement and also for movement in a direction toward and from the front of the loom, a shuttle having an opening for the entrance 100 of the feeler on a detecting beat, a protector 105

curtain of flexible material which is secured to the shuttle to cover the entrance opening and extends longitudinally of the opening to form a bearing for the end of the feeler 5 for its full side-slipping movement to protect the filling and filling carrier from injurious contact by the feeler, and means for replenishing the filling when the feeler slides along the flexible curtain on a detecting beat.

6. In a feeler mechanism for looms, the combination of a feeler that is mounted for side-slipping movement and also in a direction toward and from the front of the loom, 15 a shuttle cooperating with the feeler and having an opening for the entrance of the feeler, a protector curtain of flexible material covering the opening in the shuttle to protect the filling from contact by the feeler 20 and forming an engaging surface along and in contact with which the feeler slides to protect the filling carrier from injury when a change of filling is called by the feeler, and yielding means for securing the flexible 25 curtain in position over the shuttle opening for permissive bodily movement inwardly by the feeler on a detecting beat.

7. In a feeler mechanism for looms, the combination of a feeler mounted for side-slipping movement, a shuttle having an 30 opening for the entrance of the feeler on a detecting beat, a protector curtain of flexible material covering the opening in the shuttle to protect the filling from engagement by 35 the feeler on a detecting beat and the filling carrier from engagement by the feeler during its side-slipping movement, and a yielding connection between the flexible curtain and the upper and lower portions of the 40 shuttle that enable the feeler to bodily displace the flexible curtain inwardly of the shuttle.

8. In a feeler mechanism for looms, the combination of a feeler mounted for side-slipping movement, a shuttle having an 45 opening for the entrance of the feeler on a detecting beat, a protector curtain of flexible material covering the opening in the shuttle to protect the filling from engagement by 50 the feeler on a detecting beat and the filling carrier from engagement by the feeler dur-

ing its side-slipping movement, and yielding strips connecting the flexible curtain and the shuttle.

9. In a feeler mechanism for looms, the 55 combination of a feeler mounted to enter the shuttle in a direction inclined to the longitudinal axis thereof, a shuttle having an opening for the entrance of the feeler, a protector curtain of flexible material covering the opening in the shuttle to protect the filling from engagement by the feeler on a detecting beat, and acting to prevent side-slipping movement of the feeler along the flexible curtain, and an auxiliary feeler 60 finger which engages the shuttle when filling is exhausted on a detecting beat and effects movement of the feeler along the surface of the flexible curtain.

10. In a feeler mechanism for looms, the 70 combination of a feeler mounted to enter the shuttle on each detecting beat, an auxiliary feeler finger adapted to engage a surface on the lay when the filling is substantially exhausted on a detecting beat and by 75 frontward pressure of said surface to effect movement of the feeler longitudinally of the shuttle, and a protector curtain interposed between the feeler and filling carrier in the shuttle and along the surface of which 80 the feeler moves as it is laterally displaced by frontward pressure against the auxiliary feeler finger.

11. In a feeler mechanism for looms, the combination of a feeler mounted for side-slipping movement, a shuttle having an 85 opening for the entrance of the feeler, a protector curtain of flexible material covering the opening in the shuttle to protect the filling from contact by the feeler and forming an engaging surface along and in contact with which the feeler slides to protect the filling carrier from contact by the feeler 90 during its side-slipping movement, and a flexible strip secured to the flexible curtain 95 and to the shuttle beyond the ends of the curtain to permit bodily movement of the curtain inwardly by the feeler.

In testimony whereof, I have signed my name to this specification.

PATRICK J. HUNT.
